UNITED STATES PATENT OFFICE.

VITA BUCHANAN, OF NEW YORK, N. Y.

CORSET.

Application filed June 27, 1921. Serial No. 480,691.

My invention relates to improvements in corsets, and the same has for its object to provide a corset which will fit perfectly, be comfortable to the wearer, and which will give to the person of the wearer a trim and graceful figure.

Further, said invention has for its object to provide a corset which may be readily adjusted in position upon the person of the wearer and snugly embrace the hips, thighs and buttocks.

Further, said invention has for its object to provide a corset whose open or separated edges may be secured together throughout their entire length and completely enclose or conceal leg embracing members extending inwardly from the opposite sides of the corset.

Further, said invention has for its object to provide a corset comprising a body portion which has the outer appearance of an ordinary corset, and is provided with portions extending from the lower rear edge of the corset and cooperating with members secured within the corset adjacent to its lower front edges and jointly serving to confine the figure without interfering with the free and unrestrained use of the legs.

Other objects will in part be obvious and in part be pointed out hereinafter.

To the attainment of the aforesaid objects and ends my invention consists in the novel details of construction, and in the combination, connection and arrangement of parts hereinafter more fully described and then pointed out in the claims.

In the accompanying drawings showing an illustrative embodiment of the invention—

40 Figure 1 is an illustrative view showing one form of corset constructed according to and embodying my said invention in position upon the wearer;

45 Fig. 2 is a front view partly broken away to show the leg-embracing members; and

Fig. 3 is a side view showing one-half or part of the corset spread out, and the parts constituting one leg embracing portion secured together.

50 In said drawings 10 designates a corset which, for the purposes of illustrating my invention is herein shown as an open front corset comprising two similarly shaped halves or parts 11 forming a body portion 12 adapted to embrace the waist, hips and

55 seat, and having leg engaging portions 13

arranged adjacent to the lower edge of the corset proper.

The halves or parts 11 are provided at the upper portions of their rear edges with eyelets 14 to receive one or more laces, as, for example, 15, for adjustably securing the said rear edges together. The front edge of one of said halves or parts 11 is provided adjacent to its upper portion with studs 16, 65 and below said studs with eyelets, and the front edge of the other of said halves or parts is provided with eyes 17 adapted to engage the studs 16, and below said eyes 17 with eyelets 17' registering with the eyelets 70 of the adjacent edge which are adapted to receive a short lace 18.

The front edges of the corset halves or parts, whether the same be a high or a low corset, are firmly secured together throughout their entire lengths by the studs 16 and eyes 17, and the lace 18, while the rear edges of the corset halves or parts are secured together by the lace 15 down to about the end of the spine of the wearer. 80

The lower rear edge of each half or part is curved downwardly and forwardly towards its side of the half or part where the same meets the downwardly and rearwardly curved lower front edge to form a 85 tab or flap 19, to which is secured one end of a stocking supporter 19' adapted to engage, at the outer side of the leg, the upper edge of a stocking.

The lower rear part or seat portion of 90 each half or part is cut away, and to the edges formed thereby is secured a substantially rectangular elastic seat insert 20 which is preferably made of elastic webbing having its elastic threads 20' extending diagonally as shown. The outer lower edge 21 of said elastic seat insert 20 is curved to meet the tab or flap 19 while the inner edge of said elastic seat insert terminates in a tapering downwardly and forwardly seat 100 conforming member or strap 22 having a blunt pointed end 23 provided along its edge with a reinforcing strip 23a in whose upper portion are provided eyelets 24, and to whose lower portion is secured the upper 105 end of a diagonal stocking supporting member 25 having an attaching device 25a at its lower end adapted to engage the upper edge of the stocking at the inner side of the leg of the wearer.

The tapering members or portions 22 form the back members or straps which, when

passed forwardly over the inner sides of the thighs, are adapted to meet or approach the free ends of rearwardly extending front tapering portions or straps 26 which are secured along their inner, substantially vertical edges to the inner sides of the corset halves or parts. The other or free end of each of said tapering members or straps 26 is also provided with a flap 27, and a reinforcing strip 28 having eyelets 29 therein registering with the eyelets 24 of the back members or straps 22 to receive a lacing 30 which may be of elastic or inelastic material, as desired.

15. The upper edges of the rear tapering members or straps 22 are so curved that when their forward free ends are secured to the rearwardly extending free ends of the front members or straps 26, the same will form a 20 more or less rounded open portion 23^b, the purpose of which is obvious.

While lacings for securing the ends of the straps 22, 26 together are herein shown and described, it is obvious that the same be detachably secured by hooks and eyes, snap fastenings, or other convenient means.

It is to be noted that by means of my improved corset construction, the hips, thighs and buttocks of the wearer are effectively 30 held to shape by the leg embracing portions or straps 22, 26, and by the action of the stocking supporters 19', 25, which tend to draw the sides and the seat portions of the corset taut and thereby efficiently shape and 35 confine the corset about and to the thighs and buttocks or seat of the wearer.

Further, it is to be noted that although I have shown the invention as applied to a corset which is formed of two parts, open at 40 both the front and back, it will be obvious that the invention is equally applicable to corsets which are open either at their front or at their back portions only.

Having thus described my said invention 45 what I claim and desire to secure by Letters Patent is:

1. A corset comprising a body portion adapted to be secured together to confine the body of the wearer, an elastic seat portion 50 therefore having a free lower edge, leg embracing members each composed of two parts; one of said parts extending downwardly and forwardly from the lower edge of said seat portion, and the other having 55 one end secured to the inner side of the front of the corset and its free end extending rearwardly, means for securing the inner ends of said parts together to embrace the thighs of the wearer, and a stocking supporting member secured to one of said parts, 80 substantially as specified.

2. A corset comprising a body portion adapted to be secured together to confine the

body of the wearer, an elastic seat therefor having a free lower edge terminating in 65 downwardly and forwardly extending parts, members each having one end secured to the inner side of the front portion of the corset adjacent to the meeting edge thereof, means for securing the ends of said parts and members together to form thigh embracing members, and stocking supporting means secured to and extending from said thigh embracing members, substantially as specified.

3. A corset comprising a body portion, an 75 elastic seat therefor and leg embracing members each composed of two tapering parts; one of said parts being formed of elastic material and extending downwardly and inwardly from the lower edge of said elastic 80 seat, and the other of said parts having one end secured to the inner side of the front portion of the corset adjacent to its respective meeting edge of the corset and its other end extending rearwardly, means for securing 85 the inner ends of said parts together, and a stocking supporting member secured to each of said elastic parts, substantially as specified.

4. A corset comprising a body portion, a 90 seat composed of a pair of substantially rectangular elastic portions at the lower rear portion of said body portion, a member extending diagonally from the free corner of 95 each of said elastic portions, members extending rearwardly from the inner front sides of the corset, means for securing the cooperating ends of said rearwardly extending members to said diagonally extending members, and stocking supporting members secured to the ends of said members extending diagonally from said elastic portions, and stocking supporting members secured to the opposite outer sides of the corset, substantially as specified.

5. A corset comprising a body portion, a seat composed of a pair of substantially rectangular elastic portions at the lower rear portion of said body portion, a member extending diagonally from the free corner of 110 each of said elastic portions, members extending rearwardly from the inner front sides of the corset, means for securing the cooperating ends of said rearwardly extending members to said diagonally extending members, and stocking supporting members secured to the opposite sides of the corset and to the ends of said members extending diagonally from said elastic members, substantially as specified.

Signed at the city of New York, in the county and State of New York, this 10th day of June, one thousand nine hundred and twenty-one.

VITA BUCHANAN
